(57) **CLAIM**

We claim the ornamental design for a pig shape silicone mold, as shown and described.

DESCRIPTION

FIG. 1 is a perspective view of a pig shape silicone mold showing our new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof, featuring section lines 8 and 9 representing subsequent views FIG. 8 and FIG. 9, respectively;
FIG. 7 is a bottom plan view thereof;
FIG. 8 is a sectional rear elevational view thereof; and,
FIG. 9 is a sectional right-side elevational view thereof.
The broken lines in the drawings are for illustrating environmental structure only and form no part of the claimed design.

1 Claim, 5 Drawing Sheets
